UNITED STATES PATENT OFFICE.

MARSHALL B. SARGENT, OF MOMENCE, ILLINOIS, ASSIGNOR TO EMERSON TYPE-WRITER COMPANY, OF CHICAGO, ILLINOIS, A CORPORATION OF MAINE.

PAPER-GUIDE FOR TYPE-WRITERS.

950,190.

Specification of Letters Patent. Patented Feb. 22, 1910.

Application filed April 20, 1909. Serial No. 491,028.

To all whom it may concern:

Be it known that I, MARSHALL B. SARGENT, a citizen of the United States, residing at Momence, in the county of Kankakee and State of Illinois, have invented certain new and useful Improvements in Paper-Guides for Type-Writers, of which the following is a specification.

This invention relates to adjustable paper guides for holding the paper firmly against the platen during the typewriting operation; and the object of the invention is to so construct and mount the guides that they may be individually adjusted to any suitable position with respect to the platen, and so that ample space will be afforded behind the rod on which the guides are mounted for erasures and for the easy manipulation of the paper.

Further objects will appear from a detailed description of the invention, which consists in the features of construction and combination of parts hereinafter described and claimed.

In the drawings, Figure 1 is a front elevation of a typewriter carriage and platen, showing the paper guides in their relation thereto; Fig. 2 a cross sectional view of the platen and carriage, showing one of the guides in elevation; Fig. 3 an enlarged sectional elevation of one of the guides; and Fig. 4 a sectional detail, taken on line 4—4 of Fig. 3.

Referring to Fig. 1, the paper guides are carried upon a rod 5 which is provided with a flat side 6, the ends of which rod are supported by forwardly projecting arms 7 formed on the end plates 8 of the carriage frame. The construction of the carriage and associated parts forms no part of the present invention and need not be described in detail. The carriage frame serves to mount a platen 9 located diagonally to the rear and below the rod 5, space being afforded behind the rod to permit the operator to manipulate an eraser when it is desired to make erasures on the paper. Each of the paper guides comprises a flat plate 10 provided, at its ends, with inturned ears 11 which are bored to receive the rod 5, and the plate 10 normally extends diagonally toward the center of the platen and is provided, at its lower end, with a curved finger 12 adapted to press against the surface of the platen, the lower edge 13 of which is slightly bent away from the platen to facilitate the initial

positioning of the paper which is fed down below the platen and over a curved guide plate 14, the forward edge of which is closely adjacent to and behind the curved lower edge of the finger 12, so that the paper will slip easily from the guide plate behind the finger. On each side of the finger 12, at its point of connection with the plate 10, is a rearwardly extending tongue 15 which overlies the platen and is curved in register with the curvature of the finger, which line of curvature, as shown in Fig. 2, is of a slightly greater radius than that of the surface of the platen, so that the paper will be pressed against the platen at a single point which is at or in proximity to the printing line. The plate 10, at its outer edge, is bent at right angles to afford an upper plate 16 which overlaps the upper edges of the ears 11 and is given a curvature commensurate with the curvature of said ears. The upper plate extends around substantially the upper half of the ears and terminates in a handle 17 which extends diagonally upward from the rod 5 and permits manipulation of the guide as a whole. The plate 10 is provided, on its inner face, with a bow spring 18 which presses against the rod 5 and is adapted to normally abut against the flat face 6 of the rod in such a manner as to hold the fingers of the guides under tension against the surface of the paper.

In use, the guides can be adjusted to any desired position along the rod and will be held against accidental longitudinal displacement by the pressure of the bow springs, which, however, are not of sufficient tension to prevent easy manual manipulation of the guides. When the paper is being initially inserted, the guides can be thrown out of contact with the platen by pressing on the handles 17, which pressure serves to lift the fingers 12 away from the platen, so that the paper can be easily inserted. Thereafter the guides can be snapped back into engaging position and held during the operation of the machine.

The construction of the guides is one which permits them to be easily stamped or blocked out of a plate of metal, each of the guides being formed of a single piece of metal, with the exception of the springs, so that the cost of the guides will be extremely small and the expense of their assembling reduced to a minimum. The ar-

angement, furthermore, is one which is extremely effective in the addressing of envelopes or other relatively thick paper, since the guides can be adjusted to leave only the necessary space between them for receiving the intended typewriting, thereby holding the surface of the envelop firmly against the platen, which is often difficult in the addressing of envelopes on typewriters of the usual character.

What I regard as new and desire to secure by Letters Patent is:

1. In a device of the class described, in combination with a platen, a rod mounted adjacent to the platen the rod provided with a flattened face, a guide comprising upper and lower plates bent at an angle to one another, one of the plates being provided, at its edges, with inwardly turned ears having holes through which the rod extends, the upper plate terminating in an angularly disposed handle, the lower plate terminating in a depending curved finger, and a bow spring connected with one of the plates and adapted to bear against the rod, for holding the guide in adjusted position when said bow spring contacts the flattened face of said rod, substantially as described.

2. In a device of the class described, in combination with a platen, a rod mounted adjacent to the platen the rod provided with a flattened face, a guide comprising upper and lower plates bent at an angle to one another, one of the plates being provided, at its edges, with inwardly turned ears having holes through which the rod extends, the upper plate terminating in an angularly disposed handle, the lower plate terminating in a depending curved finger, the lower plate being further provided on each side of the finger with upwardly extending tongues, and a bow spring inter-

posed between one of the plates and the rod, for holding the guide in adjusted position when said bow spring contacts the flattened face of said rod, substantially as described.

3. In a device of the class described, in combination with a platen, a rod mounted adjacent to the platen the rod provided with a flattened face, a guide comprising upper and lower plates bent at an angle to one another, one of the plates being provided, at its edges, with inwardly turned ears having holes through which the rod extends, the upper plate having connected therewith a handle, the lower plate terminating in a depending curved finger, and a bow spring connected with one of the plates and adapted to bear against the rod for holding the guide in adjusted position when said bow spring contacts the flattened face of said rod, substantially as described.

4. In a device of the class described, in combination with a platen, a rod mounted adjacent to the platen the rod provided with a flattened face, a guide comprising upper and lower plates bent at an angle to one another, one of the plates being provided, at its edges, with inwardly turned ears having holes through which the rod extends, the upper plate terminating in a handle the lower plate terminating in a depending curved finger, the lower plate being further provided, on each side of the finger, with upwardly extending tongues, and a bow spring interposed between one of the plates and the rod for holding the guide in adjusted position when said bow spring contacts the flattened face of said rod, substantially as described.
